ILIA E. MOUROMTSEFF, OF WILKINSBURG, PENNSYLVANIA, ASSIGNOR TO WESTINGHOUSE ELECTRIC & MANUFACTURING COMPANY, A CORPORATION OF PENNSYLVANIA

SPACE CURRENT DEVICE

Application filed September 26, 1925. Serial No. 58,814.

My invention relates to space-current devices and particularly to such devices which are adapted to effect translation of substantial quantities of energy at high potentials.

An object of my invention is to increase the durability of a high-capacity vacuum tube.

Another object of my invention is to reduce the effect of ionization and corona discharge upon the structure of a vacuum tube.

Another object of my invention is to provide means for strengthening the seal construction and to reduce the breakage of the seal member in a vacuum tube.

In the construction of high-potential vacuum tubes, it is customary to employ a tubular metal anode having thinned edges and a glass closure sealed thereto. The glass closure is provided with a re-entrant portion embodying a press through which seal wires extend to supply and support a filamentary cathode. The same re-entrant portion is used to support a grid electrode by means of a clamping band which is positioned around the re-entrant portion and which has attached to it the main supporting members of the grid structure.

Difficulty has been experienced in this construction because of the relatively short creepage distance across the surface of the glass from the grid band to the cathode leads. Difficulty has also been experienced with ionization of air surrounding the cathode seal wires where they pass through the seal into contact with the outside atmosphere. This ionization is caused by the high electrostatic potential between the grid band and the cathode leads, which potential is concentrated by the close spacing between the grid band and the wires.

My invention provides means both for increasing the creepage distance and for reducing the ionization at the cathode lead wires.

Other objects and structural details of my invention will be apparent from the following description, when read in connection with the accompanying drawing, wherein:

The single figure is a view, in section, of an embodiment of my invention.

In the drawing, an anode 1 having thinned edges, has sealed thereto a glass portion 2. A re-entrant portion 3 is sealed to the member 2 and has at its inner end a press 4 through which cathode lead wires 5 and 6 are inserted. A jacket tube 7, somewhat larger than, and surrounding the re-entrant portion 3, is sealed to the re-entrant portion near the point of its attachment to the member 2. Upon the jacket tube 7 is positioned a grid-supporting band 8 to which are suitably attached the grid-support wires 9 and 10. Electrical connection is made to the grid by means of a conductor 11 and a seal wire 12 which is coiled at its inner end and flexibly attached to the lead wire 11.

My invention requires that the grid band 8 be positioned even with, or above the top of the press 4 rather than below the lower edge of the press, as shown by the dotted lines 13, which indicate the customary position of the grid-supporting band of prior constructions.

By this construction, the grid-supporting band is firmly positioned in a suitable location, whereby ample creepage distance is provided between it and the point of emergence of the cathode lead wires from the seal.

Simultaneously, the grid-support band is positioned at a point sufficiently remote from the point of emergence of the cathode seal wires on the air-exposed side of the seal to give a distribution of electrostatic stresses such that the potential at the surface of the seal wires where they emerge from the press is below the ionization potential of the air at atmospheric pressure. The lower potential avoids the production of corona discharge at the surface between the metal and glass with air which, in turn, avoids the destructive effect of such a discharge upon the glass and thus strengthens the seal and enables it to perform the desired function for a much longer period of time.

While I have shown but a single embodiment of my invention in the accompanying description, it is capable of various changes and modifications and it is desired, therefore, that only such limitations shall be imposed

thereon as are indicated by the prior art or by the appended claims.

I claim as my invention:

1. A space-current device with an external 5 anode comprising an evacuated vitreous-material container having a re-entrant portion extending upwardly therein, a press on the upper end thereof, a conductive lead extending through said press, an electrode at- 10 tached to said lead, a vitreous-material sleeve surrounding said re-entrant portion and at- tached thereto, a second electrode attached to a supporting band on said sleeve, said band being positioned above the air-exposed side 15 of the press, and a conductive lead attached to said band.

2. A space-current device with an external electrode comprising an evacuated vitreous- 20 material container having a re-entrant portion extending upwardly therein, a press on the upper end thereof, a conductive lead ex- tending through said press, an electrode at- 25 tached to said lead, a vitreous-material sleeve surrounding said re-entrant portion and at- tached to and supported by the intermediate 30 part of said re-entrant portion, a conductive supporting band on said sleeve substantially in the plane of said press and positioned above the air-exposed side of the press, and a second electrode attached to said band.

In testimony whereof, I have hereunto sub- 35 scribed my name this 17th day of September, 1925.

ILIA E. MOUROMTSEFF.
